FIG. 6

UNITED STATES PATENT OFFICE.

CHARLES F. CLARK, OF BOSTON, MASSACHUSETTS, ASSIGNOR TO THE CLARK MANUFACTURING COMPANY, OF SAME PLACE.

BOOT OR SHOE TREE.

SPECIFICATION forming part of Letters Patent No. 569,857, dated October 20, 1896.

Application filed July 8, 1895. Serial No. 555,837. (No model.)

To all whom it may concern:

Be it known that I, CHARLES F. CLARK, of Boston, county of Suffolk, and State of Massachusetts, have invented an Improvement in 5 Boot or Shoe Trees, of which the following description, in connection with the accompanying drawings, is a specification, like letters on the drawings representing like parts.

This invention is intended as an improvement upon the machine for holding boots and 10 shoes while being operated upon shown and described in United States Patent No. 417,148, granted December 10, 1889, and No. 543,147, granted July 23, 1895, to G. H. Clark; and it 15 consists in many details of construction to be hereinafter pointed out.

Figure 1 shows in front elevation a machine for holding boots and shoes while being operated upon embodying my invention; Fig. 2, 20 an enlarged side elevation and partial section of one of the expandible legs or trees; Fig. 3, a plan view of the leg or tree shown in Fig. 2, the fore part being removed; Fig. 4, a detail of the treadle mechanism; Fig. 5, a detail 25 of the locking device for the expanding device of the tree, and Fig. 6 a detail of the locking device for the shaft carrying the trees.

The main frame A, having bearings at its upper end for a horizontal shaft h^2 , to which 30 is secured a disk or hub h' , having upon one side of it sockets i for the trees or legs, which are provided with cylindrical end pieces fitting said sockets in order that they may be freely rotated therein, and set-screws i' for 35 holding the legs or trees in said sockets, and also for restraining them from rotating therein when desired, the bell-crank lever e , pivoted to the framework and having an in-turned end which engages a pin d' , projecting 40 through the end pieces of the trees, said pins being connected with the wedges d , by means of which the parts b c of the trees are separated, the treadle t^2 , and its treadle-rod t , connected with said bell-crank lever e , are all 45 substantially as represented in G. H. Clark's improved machine.

The block or plate f , sliding in a cut-away portion of the part c of the tree, is herein provided at its outer end with a keyhole-slot f' 50 and at its inner end with a sliding spring-bolt g^2 , having a finger-piece g^3 for moving it.

The fore part g , herein represented as a foot-piece and an attached shin-piece g^10 , is detachably connected with said sliding block or plate f by means of a headed stud g' , projecting rearwardly from the rear side of the fore part near its sole face and entering the keyhole-slot f' , formed in the plate f , and by the aforesaid spring-controlled bolt g^2 , which enters a socket formed in the upper end of 60 the shin-piece g^10 .

As a specific means of locking the sliding plate f when the parts b c are separated I have provided a bell-crank lever n , pivoted at n' to the part c , one arm of which has a 65 latched end n^2 , which enters a socket or engages a shoulder formed on the sliding plate, and the other arm of which is acted upon by a spring n^3 , which tends to hold the latched end removed from engagement with the sliding plate f .

The arm which is acted upon by the spring lies in the path of movement of the wedge d , so that when said wedge is moved forward to separate the parts b c it will strike the bell-crank lever n and throw its latched end into 70 engagement with the sliding plate.

Independent locking devices are provided for the trees, whereby the parts thereof may be held separated different distances, yet released at any time desired by hand, and also released automatically at a predetermined point in the rotation of the hub or shaft carrying said trees, said locking devices each consisting of a notched pin d' , which projects 80 axially through the end piece of each tree and which is connected with the expanding-wedge d , the notches on said pins being formed circumferentially, and a pawl-like engaging device for each notched pin. Said engaging 85 device consists of a plate fitted to slide diametrically across the end piece in a dovetailed groove formed therein, said plate being slotted, as at d^4 , to receive the notched pin d' , the slot permitting a limited longitudinal movement of said plate, and said plate has at one end a pin d^5 , projecting through the disk h' , which is encircled by a short spiral spring d^6 , the action of which is to draw the slotted plate toward the disk. 95

The notches formed in the pin d are made of such shape as to present circumferential

ratchet-teeth, and a thin plate d^8 is adjustably secured by a screw d^9 to the under side of the plate d^8 , the inner edge of which projects over the slot d^4 for a short distance, and this inner end engages the notched pin d' , acting as a pawl.

By operating the treadle t^2 the bell-crank lever e is operated, engaging one or another pin d' and moving it inward that the wedge 10 connected therewith may expand the tree, and the pin so moved is held by means of the spring-controlled pawl-like plate d^8 in any position that it may be set.

By depressing any one of the pins d^6 by hand or otherwise at any time the pawl-like engaging device is disengaged from the pin d' and the latter permitted to retract. I have also secured to the framework a short arm or projection m , which lies in the path of the pins d^6 as they are turned with the hub or disk h' , and whenever one of said pins d^6 strikes said arm m it will be positively pushed inwardly, releasing the pin d' .

As a means of locking the shaft h^2 in its different positions I have secured to said shaft a disk o^4 , having sockets or holes in number and position corresponding to the number of trees on the shaft, and a spring-pressed pin o^3 passes through the frame adapted to enter any hole in the disk o^4 . A cam-block o^2 is placed just back of the head of said pin o^3 , which astrides the pin, and as it is moved up and down the pin is permitted to enter any hole in the disk or is withdrawn therefrom. The cam-block o^2 is attached to the upper end of a rod o' , passing down alongside the frame and connected at its lower end with a treadle o . By depressing said treadle o the cam-block is operated to withdraw the pin o^3 .

The treadle t^2 has pivotally connected to it a latch p , which when the treadle is depressed engages a rod p' and thereby locks the treadle in its depressed position. An intermediate locking-lever p^2 is pivotally connected to the frame between the treadles t^2 and o , one end of which is hook-shaped to engage a treadle o , while the other end rests upon or is connected with the treadle t^2 , and when the treadle t^2 is depressed the locking-lever p^2 moves to engage and lock the treadle o , but when the treadle t^2 is again elevated the locking-lever p^2 will be restored. Hence it will be seen that the treadle o cannot be operated when the treadle t^2 is depressed.

I claim—

1. A boot or shoe tree composed of the front and back leg parts, the plate f sliding in a cut-away portion of the front leg part, having at its outer end the keyhole-slot f' , and

at its inner end the spring-pressed pin g^2 , with finger-piece g^3 , and the fore part g having on its rear side the headed stud g' , which enters said keyhole-slot f' , and having at its upper end a socket which receives the pin g^2 , substantially as described.

2. A boot or shoe tree comprising front and back leg parts, the sliding plate f on the front leg part, having at its inner end the spring-pressed pin g^2 with finger-piece g^3 , the fore part g having at its upper end a socket which receives said pin g^2 , and means for detachably connecting the lower end of said fore part with said sliding plate, substantially as described.

3. The separable parts b , c , of the tree, wedge d for separating them, sliding plate f and fore part, combined with the bell-crank locking-lever n for said plate f , pivoted to the part c , one arm of which lies in the path of movement of said wedge d , to be moved by it to lock the plate.

4. The separable parts b , c , of the tree, wedge d for separating them, sliding plate f having a notch in its under side, and a fore part, combined with the bell-crank locking-lever n , for said plate, pivoted to the part c , one arm of which has a latched end n^2 which enters the notch in said plate f to lock it, and the other arm of which lies in the path of movement of said wedge d , to be moved by it, and the spring n^3 , substantially as described.

5. In a machine for holding boots and shoes while being operated upon, a rotatable disk, two or more trees supported thereby provided with expanding devices, a bell-crank lever for operating any one of said expanding devices, a treadle with which it is connected, a locking-pin o^3 for the shaft of said rotatable disk, cam-block o^2 for withdrawing it, a treadle connected with said cam-block, and an intermediate locking-lever between said treadles.

6. The expandable form comprising the parts b , c , sliding plate on the part c , and fore part borne by it, and an expanding device for said form, combined with a bell-crank locking-lever for said sliding plate operated by said expanding device, one arm of said lever being adapted to engage and hold said plate and the other arm to be engaged by said expanding device, substantially as described.

In testimony whereof I have signed my name to this specification in the presence of two subscribing witnesses.

CHARLES F. CLARK.
